(57) **CLAIM**

The ornamental design for a current inverter, as shown and described.

DESCRIPTION

1. Current inverter

1.1 : Front

1.2 : Back

1.3 : Left

1.4 : Right

1.5 : Top

1.6 : Bottom

1.7 : Perspective

1.8 : Perspective

Reproduction 1.1: front view of design 1; Reproduction 1.2: back view thereof; Reproduction 1.3: left view thereof; Reproduction 1.4: right view thereof; Reproduction 1.5: top view thereof; Reproduction 1.6: bottom view thereof; Reproduction 1.7: perspective view (front, bottom, right side) thereof; Reproduction 1.8: perspective view (back,top, left side) thereof.
